UNITED STATES PATENT OFFICE

ALPHEUS O. HURXTHAL, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA

PANEL FOR DRIERS

Application filed April 13, 1926, Serial No. 101,841. Renewed July 15, 1929.

One object of my invention is to provide a panel for use in the manufacture of driers and like structures, where panels or sections consisting of inner and outer sheets are spaced apart with non-conducting material between them.

Another object of my invention is to reduce the quantity of standard panels necessary to carry in stock in order to build standard machines.

A further object of the invention is to provide a substantial means for supporting the necessary machine mountings or other structural members at any place, either on the inside or the outside of the panel.

And a still further object of the invention is to provide means which not only acts as a support for machine or structural members but also aids in stiffening the panel.

These objects are attained in the following manner; reference being had to the accompanying drawings, in which:

Fig. 1 is a side view of my improved panel; Fig. 2 is a sectional view on the line directly back of the front sheet;

Fig. 3 is a sectional view on the line 3—3, Fig. 1, drawn to a larger scale;

Fig. 4 is an enlarged sectional view showing a punched channel member located between the front and back sheets of the panel, the sheets being solid;

Fig. 5 is a face view of the front sheet cut to expose the channel and an opening therein, the hole in this instance being circular in form;

Fig. 6 is a view illustrating the hole in the inside sheet which is rectangular in form and in line with one of the holes in the channel;

Fig. 7 is a sectional plan view similar to Fig. 4 but showing the front sheet punched and a machine element secured to the channel;

Fig. 8 is a similar view to Fig. 4, showing the rear sheet punched and a structural member secured against the inner sheet; and

Fig. 9 is a perspective view of a bolt.

The drawings illustrate panels particularly used in connection with drying machinery, in which heated air is circulated to dry material located within the drier or traversing

through the drier. The channel shown in Fig. 8 is one of the rails on which the carriers travel, while Fig. 7 shows a fan bracket, but it will be understood that the invention can be used for any type of drier or other machine requiring an insulated casing, and where the inner and outer sheets are not of sufficient strength in themselves to support the machine elements or structural work.

Referring to Figs. 1, 2 and 3, 1 is a panel made of two thin sheets of steel or other metal, the outside sheet 2 of the panel having a deep flange 3 which is extended as at 4 to rest against the flanges 6 of the inner sheet 5. The two surfaces are welded together by spot-welding at "x". 7 are reinforcing angles located at the corners of the outer sheet. 9—9 are two channel members vertically arranged in the present instance and extending the full height of the panel. The channel is welded at "y" to the inner sheet and is spaced from the outer sheet. Any suitable non-conducting material is located between the two sheets of the panel. This non-conducting material is preferably corrugated asbestos board, and this asbestos non-conducting material extends between the front sheet and the channel member as clearly shown in Fig. 4, so as to prevent through-metal contact from the inside of the drier to the outside at this point.

In some instances the channel members may be welded or otherwise secured to the outside sheet and spaced from the inside sheet. While I have shown the channels arranged vertically, they may be arranged horizontally in some instances or at any angle, depending particularly upon the character of the sheet and arrangement of the panel.

The channel members have a series of holes punched in each flange as shown, and these holes are of such a distance apart as to permit the mounting of any machine elements or structural members at practically any place either on the inner side or outer side of the panel.

When the panel is assembled, the inner and outer sheets are not punched but are solid, as shown in Figs. 1 and 4, and when it is

desired to secure a machine element to the outside of the panel, as in Fig. 7 for instance which illustrates a bearing bracket 12, then the outer sheet is preferably punched and the 5 asbestos or other non-conducting material exposed at this opening is removed so as to allow the machine element to come in contact with the channel member.

In this instance, the hole 13 in the front 10 sheet is circular and the bracket 12 has a corresponding boss 14 which extends into the hole and bears against the flange of the channel member 9. The hole in the channel member is elongated as shown in Fig. 5. A 15 bolt 15, Fig. 9, is used, having an elongated head 16 which can be passed through the opening 11 in the channel member and turned at right angles so that the head will overlap the sides of the opening. This bolt extends 20 through the bracket 12 as shown in Fig. 7, and a nut 17 is applied to the bolt which firmly secures the bracket to the channel member.

If a rail or other structural member 18, 25 Fig. 8, is to be secured to the inner side of the panel, then a rectangular hole 19 is cut in the inner sheet 5 in line with one of the openings 11 in the channel member as in Fig. 6 and a bolt 15^a of the same general type 30 as the bolt shown in Fig. 9 is inserted in the elongated rectangular opening, while a nut 17^a is applied which secures the structural member 18 rigidly to the channel member. In this instance the structural member rests 35 directly against the inner sheet which is in contact with the inner flange of the channel.

By the foregoing description of this invention it will be noticed that the number of panels necessary to be carried in stock is 40 greatly reduced, as panels having special punchings to suit different types of driers need not be provided, as the panels can be punched if necessary after being set up, so as to allow the machine elements or structural 45 work to be firmly secured either to the outside of the panel or to the inner side thereof.

The perforations in the channels can be located so close together that they permit the mounting of any machinery or structural 50 member at any place desired. The channel members also naturally strengthen the panel, and the inner and outer sheets may consequently be made of lighter material than heretofore, where the machine elements or 55 structural members were secured directly to the sheets of the panel.

While I have shown a particular form of 60 panel in which the outer sheet is flanged and securely welded to the inner sheet, the invention can be applied to other forms of panels without departing from the essential features of the invention; and while I have used the term "panel", it is to be strictly understood 65 that it is to cover any structural wall using spaced inner and outer sheets, between which

is provided an air space or a space for non-conducting material.

Furthermore, while I have shown both flanges of the channel members perforated so that the machine elements or structural work can be attached to either side of the panel, in some instances, where the machine elements or structural work is secured to one side only, then the flange of the channel at that side may be perforated only, while the 70 other side may be solid. 75

I claim:—

1. The combination of inner and outer plates spaced apart; and a channel member located between the plates, the channel member having a series of perforations in line with one of said plates, so that the plate can be punctured at one of the perforations to allow a bolt or other fastening to be attached to the channel member by which a machine element or structural member can be secured to the channel. 80

2. The combination of inner and outer sheets spaced apart with channel members located between the plates, the channel members being perforated at intervals so that when the structure is assembled the inner or outer sheets can be perforated at a point in line with one of the perforations in the channel so that a machine element or structural member can be secured to the channel members. 95

3. The combination in a panel, of inner and outer sheets spaced apart and secured at their edges; and channel members within the panel and located between the inner and outer sheets, the flanges of said members lying parallel with the sheets and having perforations therein so that either sheet can be perforated in line with one of the perforations in one of the channel members for the reception of securing means for machine elements or structural members. 100

4. The combination in a panel, of two inner and outer sheets spaced apart and secured together at their edges; and a channel member within the panel and located between the inner and outer sheets, the flange of the channel member being in contact with and secured to one of said sheets and spaced from the other sheet, said channel member being perforated at intervals so that one of the sheets may be perforated in line with the perforations in the channel, to allow for the attachment of securing means for machine elements or other structures. 110

5. The combination in a panel, of inner and outer sheets spaced apart and connected at their edges; non-conducting material located between the sheets; and a channel member located within the panel between the sheets, the flange of the channel member being perforated at intervals so that the sheets can be punctured to allow fastening means to engage the channel member. 125

6. The combination in a panel, of two sheets spaced apart; non-conducting material in the space between the sheets; and channel members located between the sheets, the flange of one member being secured directly to one of said sheets and spaced from the other sheet, the non-conducting material extending between the sheet and the channel, said channels being perforated at intervals so that a sheet can be perforated in line with the perforations in the channel, to allow for the attachment of securing means directly to the channels.

10 7. The combination in a panel, of two inner and outer sheets; a channel member located in the space between the sheets and secured to one of said sheets and spaced from the other sheet; non-conducting material in the space between the two sheets and extending between the channel and one of said sheets, said channel member being perforated at intervals, the sheet which is spaced from the channel member having a perforation greater in size than the perforation in the channel; a machine element having a boss extending through the perforation in the sheet and bearing directly against the channel member; and a bolt for attaching the machine element directly to the channel member.

15 8. The combination in a panel, of two inner and outer sheets spaced apart, the sheets being connected at their edges; two vertically arranged channel members extending from one end of the sheet to the other, said channel member being secured directly to the inner sheet and spaced from the outer sheet; and non-conducting material in the space between the sheets, said material extending between the channel and the outer sheet, the flanges of the channels being perforated at close intervals so that either sheet can be perforated in line with any one of the perforations, to allow for the attachment to the panel of machine elements or structural work.

20 9. The combination in a panel, of inner and outer sheets spaced apart; and a perforated member located between the two sheets and arranged so that when one of said sheets is perforated a machine element can be attached to said perforated member through the perforations in the sheet.

25 10. The combination in a panel, of inner and outer plates spaced apart; and an angular member located between the plates, said member having a series of perforations near one of the plates, so that said plate can be punched at one of the perforations to allow a fastening means of a machine element or structural member to be attached to the said angular member through the plate.

ALPHEUS O. HURXTHAL.
